Primary Examiner — Karen E. Eldridge Powers*Assistant Examiner* — Jasmine Mlinarcik(74) *Attorney, Agent, or Firm* — Kirk A. Buhler; Buhler & Associates(57) **CLAIM**

The ornamental design for a cap with changeable brim and snap fastener covers, as shown and described.

DESCRIPTION

FIG. 1 is a top perspective view for a cap with changeable brim and snap fastener covers showing my new design;

FIG. 2 is a front side elevation view thereof;

FIG. 3 is a rear side elevation view thereof;

FIG. 4 is a left side elevation view thereof;

FIG. 5 is a right side elevation view thereof;

FIG. 6 is a top side plan view thereof;

FIG. 7 is a bottom side plan view thereof; and,

FIG. 8 is an exploded side perspective view showing the cap with changeable brim and snap fastener covers.

The cap depicted in broken lines in FIGS. 1-8 illustrates environmental subject matter that forms no part of the claimed invention.
